UNITED STATES PATENT OFFICE.

JOHN YOUNG, OF NEW WESTMINSTER, BRITISH COLUMBIA, CANADA.

CRUDE-OIL BURNER.

1,227,867.

Specification of Letters Patent.

Patented May 29, 1917.

Application filed January 6, 1917. Serial No. 140,917.

To all whom it may concern:

Be it known that I, JOHN YOUNG, a citizen of the Dominion of Canada, residing at New Westminster, in the Province of British Columbia, Canada, have invented certain new and useful Improvements in Crude-Oil Burners, of which the following is a specification.

This invention relates to a crude oil burner for a boiler furnace or the like, and belongs to that class wherein the oil is sprayed from the burner by steam under pressure, the oil in a finely divided state being delivered from the burner outlet with the steam.

In all burners of this class with which I am acquainted the oil is delivered through small apertures in a central pipe into a concentrically disposed pipe through which the steam is delivered. This system is open to objection in that the apertures through which the oil is delivered are subject to obstruction.

This objection is overcome in the invention, which is the subject of this application, and an exceedingly simple and effective burner is produced, by delivering the steam through a central pipe and the oil through the concentric interspace between it and an outer pipe, which interspace is restricted, enlarged and again restricted at the burner. At the first annular enlargement and adjacent the second restriction a series of small apertures deliver the steam from the inner pipe to the enlarged annular space, the apertures being angled to induce a forward movement toward the burner outlet and a gyroscopic movement within the interspace. From the second restriction the combined oil and steam under pressure is abruptly delivered into a mixing chamber before delivery to the outlet.

The invention is particularly described in the following specification, reference being made to the drawings by which it is accompanied, in which:

Figure 1 is a general view of the burner showing the connection of the oil and steam pipes thereto.

Fig. 2 is a longitudinal section to an enlarged scale of the burner.

Fig. 3, a cross section on the line 3-3 in Fig. 2, and

Fig. 4, an enlarged section on the line 4-4 in Fig. 2.

The burner comprises a member 2 which

is axially bored and is threaded at one end to receive the oil pipe 3 and at the other end is reduced to a relatively smaller burner outlet 4, which outlet is threaded with a coarse standard screw thread. Intermediate of the ends the member 2 is bored cylindrical to a dimension between that of the bore at 3 and 4, the change of dimension being at both ends abrupt and conical at an angle of approximately one hundred and ten degrees.

Steam is delivered to the burner through a pipe 6 which passes axially through the oil pipe 3 for a distance of about eighteen inches from the T 7 to which the oil service pipe is connected, being supported in the T by a reducer 8. Threaded on the end of this steam pipe 6 to project within the burner 2 is a member 10 which beyond the end of the pipe 6 is conically reduced to a dimension approximating that of the steam pipe and toward the end is again abruptly enlarged, as at 11, to a dimension slightly less than the cylindrical bore of the burner 2. This end 11 is blind and square across and is a short distance from the burner outlet 4 so as to leave a chamber space 12 between the end of the inner member 10 and the conical reduction of the burner 2 at the outlet.

The reduction of the diameter of the member 10 at the end to which the steam pipe 6 is connected is conical to an angle approximating one hundred and ten degrees and into the conical slope of this reduction a series of small apertures 13 are drilled normal to the slope and at a slight angle to the radius to impart a swirling movement to the steam and oil in the enlarged interspace, and at the other end of this interspace, that is, adjacent the enlarged end 11 of the member 10 is another series of small apertures 14 drilled at a similarly slight angle to the radius.

With a burner so constructed, the oil is delivered to the burner through the pipe 3 and before reaching the burner is well heated by the steam passing to the burner through the central pipe 6. This oil is checked in its flow as it passes through the restricted annular space between the inside of the pipe 3 and the outside of the inner member 10 where it is secured on the end of the pipe 6, so that there is no flooding of the burner with oil, while the heat and vibration of the inner pipe will tend to free any tendency to obstruct at this restriction.

As the oil emerges from this restriction it

is met by the jets of steam issuing through the apertures 13 and 14. The oil is thereby broken up into a finely divided state before it meets the restriction which the end 11 of the inner pipe makes with the cylindrical bore of the burner 2. This finely divided oil and steam under pressure expands freely from the restriction at the end 11 into the chamber space 12 and in that expansion is further finely divided and mixed together ready for issuance through the burner outlet 11. The screw thread of this burner outlet prevents the jet of gaseous fuel being projected too far into the furnace as it holds back the outer zone of the jet, so that it is in a better condition to mix with the air for combustion which is admitted through the furnace front adjacent the introduction of the burner pipe therethrough.

20 The steam service pipe 6 is trapped of any water of condensation by connecting it to the branch of a T to the straight line connection of which a drain pipe 9 is connected.

Having now particularly described my invention, I hereby declare that what I claim as new and desire to be protected in by Letters Patent, is:

1. A crude oil burner, comprising in combination, an outer pipe to which an oil service is connected, a steam pipe passing axially through it, an outer burner member secured to the end of the oil pipe, said member axially bored and abruptly reduced at its end to a burner aperture, an inner burner member secured on the end of the inner pipe to project within the outward member to a short distance from its outlet, said inner member axially bored in alignment with the steam pipe to a short distance from its end, the end diameters of the inner member being such as will leave restricted annular spaces between them and the bore of the outer member, and intermediate of its ends reduced in diameter to leave a larger annular space between the restrictions, said intermediate reduced portion having a series of small apertures delivering into the said larger annular space.

2. A crude oil burner, comprising in combination, an outer pipe to which an oil service is connected, a steam pipe passing axially through it, an outer burner member secured to the end of the oil pipe, said member axially bored and abruptly reduced at its end to a burner aperture, an inner burner member secured on the end of the inner pipe to project within the outward member to a short distance from its outlet, said inner member axially bored in alignment with the steam pipe to a short distance from its end, the end diameters of the inner member being such as will leave restricted annular spaces between them and the bore of the outer member, and intermediate of its ends reduced in diameter to

leave a larger annular space between the restrictions, said intermediate reduced portion having a series of small apertures delivering into the said larger annular space, said apertures being angled forward and angled to a radius to impart a forward gyroscopic movement to the fluid within the enlarged annular space.

3. A crude oil burner, comprising in combination, an outer pipe to which an oil service is connected, a steam pipe passing axially through it, an outer burner member threaded onto the oil pipe and axially bored cylindrical to a diameter which is conically reduced from that of the thread and at the opposite end is abruptly reduced to a circular delivery outlet, an inner burner member secured on the end of the inner pipe to project within the outer member to a short distance from its outlet, said inner member conically reduced in diameter adjacent the conical reduction of the outer member and again abruptly enlarged adjacent the end to a diameter slightly less than the cylindrical bore of the outer member, said inner member provided with a series of small apertures at the conical reduction which are normal to the surface of the cone and angled slightly from the radial line, and another series of small apertures adjacent the end enlargement which apertures are similarly angled to the radius.

4. A crude oil burner, comprising in combination, an outer burner member axially bored and threaded to fit an oil service pipe and therebeyond conically reduced to a cylindrical bore which at the farther end is abruptly reduced to a circular delivery outlet, an inner burner member the outside diameter of which at one end is larger than the cylindrical bore of the outer member and at the other end has a diameter slightly less than the cylindrical bore of the outer member and intermediate of its ends is reduced below the diameter of the outer end the reduction at the larger end being conical to correspond with the conical reduction of the bore of the outer member, said inner member being axially bored to a short distance from its end which end terminates a short distance from the delivery aperture of the outer member, the inner member being provided at its conical reduction with a series of apertures normal to the surface of the cone but angled from the radius and at the other end of the reduced portion has a series of apertures similarly angled to the radius, and means for connecting a steam service to deliver to the bore of the inner member.

5. A crude oil burner, comprising in combination, an outer burner member axially bored and threaded at one end to fit an oil service pipe and therebeyond conically reduced to a cylindrical bore which at the

farther end is abruptly reduced to a circular delivery outlet threaded with a screw thread, an inner burner member the outside diameter of which is at one end larger than the cylindrical bore of the outer member and at the other end has a diameter slightly less than the said cylindrical bore and intermediate of its ends is reduced below the diameter of the outer end, the reduction at the larger end being conical to correspond with the conical reduction in the bore of the outer member, the outer end

of the inner member terminating a short distance from the outlet reduction of the outer member so as to leave a chambered interspace, the inner member being axially bored to a short distance from its outer end and having a series of small apertures through it at the intermediate reduced portion, and means for delivering a steam service to the bore of the inner member.

In testimony whereof I affix my signature.

JOHN YOUNG.
